UNITED STATES PATENT OFFICE.

LEROY A. WILLIAMSON, OF BOSTON, MASSACHUSETTS.

PORTABLE ELECTRIC-LIGHT FIXTURE.

1,027,634.

Specification of Letters Patent.

Patented May 28, 1912.

Application filed October 13, 1910. Serial No. 586,887.

To all whom it may concern:

Be it known that I, LEROY A. WILLIAMSON, of Boston, county of Suffolk, and State of Massachusetts, have invented certain new and useful Improvements in Portable Electric-Light Fixtures; and I do hereby declare the following specification, taken in connection with the accompanying drawings, forming a part of the same, to be a full, clear, and 10 exact description thereof.

My invention relates to an improved form of portable electric light fixture of the same general character as the fixture forming the subject of my Letters Patent, No. 914,772, 15 dated March 9, 1909.

It is the object of the present invention to provide a form of portable electric light fixture which is extremely simple in construction and cheap to manufacture.

20 To that end the invention consists in the novel construction, arrangement and combination of parts hereinafter described and claimed, reference being made to the accompanying drawings, in which—

25 Figure 1 is a side elevation of my improved form of portable fixture showing the same in use. Fig. 2 is a similar view showing the fixture out of use and with one side removed or broken away. Fig. 3 is a trans- 30 verse sectional view through the center of the device.

Referring to the drawings, A represents the casing and B an attaching plug which is preferably made as a part of the casing. 35 Journaled in the walls of the casing A is a hollow hub a, in which is a spring b. The outer end of the spring b is fastened to the hub a at c and the inner end of said spring is fastened to a stud d which passes through 40 the hub a and is secured at each end to the walls of the casing. In the hub a is a trans- 45 verse partition e which is provided upon one side with ratchet teeth f which are arranged and adapted to engage the teeth upon a ratchet-wheel g which is splined upon the stud d. The stud d is provided with a longitudinal slot h and surrounding said stud is a coiled spring i, one end of which bears 50 against the ratchet-wheel g and the other end of which bears against one of the walls of the casing A. Mounted to slide longitudinally in the stud d is a pin l, the inner end of which is connected to the ratchet-wheel g.

55 On one end of the hub a are two metal rings a' which are in frictional engagement with two metal rings a² on the inside of one of

the walls of the casing A. The metal rings a are connected by a quantity of lamp cord j' wound on the hub a to a lamp socket k, and the metal rings a² are connected by 60 wires j to the plug B.

The operation of the device is as follows: Remove the lamp from the stationary fixture and insert plug B into said fixture. Then draw lamp socket k out of casing A 65 and insert the lamp taken from the stationary fixture therein. Then draw as much of the cord j' out of the casing as is desired. As the cord is drawn from the casing the hub a will revolve and thereby wind up the spring 70 b and when the desired amount of cord has been withdrawn the hub will be held against movement from the action of the spring by the ratchet wheel g. When now the user has ceased using the device he simply pushes in 75 the pin l, thereby throwing the ratchet-wheel out of engagement with the ratchet-teeth f and the hub a will be revolved by the spring b in a direction to wind up the cord and draw the socket k into the casing. 80 As soon as the socket k is partly or wholly within the casing, pressure is removed from the pin l and the spring i will force the ratchet-wheel g back into contact with the ratchet-teeth f and the hub a will thus be 85 locked against further revolution in a direction to wind up the cord.

What I claim as my invention and desire to secure by Letters Patent is:

1. In a device of the character described, 90 the combination, with a suitable casing, of an attaching plug upon the exterior thereof, a hub mounted to revolve upon the interior of said casing, a quantity of electric lamp cord wound on said hub, a lamp socket at- 95 tached to one end of said cord, means connecting the other end of said cord to the attaching plug, spring-actuated means for revolving the hub in one direction, and means for locking the hub against revolution in 100 one direction.

2. In a device of the character described, 105 the combination, with a casing, of an attaching plug upon the exterior thereof, a hollow hub mounted to revolve within said casing, a spring arranged to revolve said hub in one direction, a series of ratchet-teeth on said hub, a ratchet-wheel adapted to normally engage said ratchet-teeth, means for moving said ratchet-wheel out of engagement with said ratchet-teeth, a quantity of lamp cord wound upon said hub, a

lamp socket on one end of said cord, and means connecting the other end of said cord to the attaching plug.

3. In a device of the character described, 5 the combination, with a casing, of an attaching plug upon the exterior thereof, a hollow hub mounted to revolve within said casing, a spring arranged to revolve said hub, a transverse partition upon the interior 10 of said hub provided with a series of ratchet-teeth, a stationary stud extending through said hub, a ratchet-wheel mounted to slide on said stud and normally held in engagement with said ratchet-teeth by means of a 15 spring surrounding said stud between said ratchet-wheel and the casing, a pin slidably

mounted in said stud and having its inner end connected to said ratchet-wheel, two metal rings upon the exterior of said hub arranged to contact with two metal rings 20 upon the interior of the casing, wires connecting the metal rings upon the casing with the attaching plug, and an electric light cord having one end connected to the metal rings upon the hub and the other end connected to a lamp socket, said cord being arranged and adapted to be wound upon the revolving hub.

LEROY A. WILLIAMSON.
